United States Patent Office.

DERK A. TER HOEVEN, OF PHILADELPHIA, PENNSYLVANIA.

Letters Patent No. 79,160, dated June 28, 1868.

IMPROVEMENT IN THE MANUFACTURE OF FERTILIZERS.

The Schedule referred to in these Letters Patent and making part of the same.

TO ALL WHOM IT MAY CONCERN:

Be it known that I, DERK A. TER HOEVEN, of Philadelphia, Pennsylvania, have invented a new "Process for the Manufacture of Horn-Dust Fertilizer;" and I do hereby declare the following is a full, clear, and exact description thereof, reference being had to the accompanying drawings, and to the letters of reference marked thereon.

The nature of my invention consists in taking hoofs and horns of animals and reducing them to powder suitable for application to the soil as a fertilizer.

To enable others skilled in the art to make and use my invention, I will proceed to describe the process of manufacture.

Figure 1 is an elevation of the steam-digester.

Figure 2 is a section through the drying-kiln.

Figure 3 is a sectional elevation through the edge or mortar-mill.

The steam-digester A is mounted on journals b b' , resting on bearings B. The journal b has a worm-wheel, c, geared on it. A worm-pinion, d¹, gears into this wheel, by means of which the digester can be dumped and its contents emptied. The other journal, b' , is hollow, through which the steam enters the digester from the steam-boiler which supplies it.

There is a drain-pipe and cock, D, by which the condensed steam is drawn off. A small arched grating, acting as a strainer, is placed over the inlet to this cock D.

The upper cock and pipe E are for blowing out the air, and for emptying the digester of steam at the conclusion of the operation.

G is the man-hole, secured by a cross-bar, g, with bolts and nuts.

Fig. 2 is the drying-kiln. The floor of this kiln is of brick, H. At one end is a series of fireplaces, ranged side by side. k¹ is the fire-door; k², the fire-bars; k³, the end wall. M is the long flue under the floor of the kiln. Each fireplace is separated by a wall running the length of the kiln, and terminating in a cross-flue, O, leading to the chimney P. R is a wooden shed raised over the kiln; r¹, ventilators to regulate the temperature of the room S.

Fig. 3 shows the edge-mill used for crushing the horns to powder. T is the trough or pan into which the prepared horns are placed. V is a stone about five feet diameter, set on edge, and turning on the shaft W, which is driven round the centre shaft X by horse or steam-power.

The operation of the process is in this way:

The horns and hoofs of animals, button-waste, and similar glutinous substances, are placed in the digester A. The steam from the boiler is turned on, from forty-to eighty pounds' pressure. At this pressure and temperature of steam, horns and button-waste will require about one and a quarter to one and a half hour. Hoofs will require two to two and a half hours. The cock D is opened from time to time to draw off the condensed water. When the necessary time has elapsed, the material is dumped out of the digester and transferred to the floor, H, of the drying-kiln. This floor is kept at a low temperature of about 170°, and the room S at 90° to 100°. The hoofs are spread about six inches deep over the floor, and in fair weather will be ready for the crusher in two or three days.

By this plan of steaming at a low temperature and drying, as described, the fertilizing properties of the horns and hoofs are preserved without deterioration.

When the hoofs are dried sufficiently brittle to break in the fingers, they are removed to the pan T and ground to powder beneath the stone, V. The finest portion is then sifted out, the shoes and iron picked out, and the coarse powder is either used for the soil or crushed over again.

I am well aware that hoofs and horns have been incidentally steamed and ground with bones in the manufacture of superphosphate and ground bone-dust. They have, however, been dried at higher temperatures, so

as to char them and make them more friable, which deteriorates the quality, and then they can only be put through a bone-mill in small quantities with the bones, on account of gumming and their glutinous properties.

I believe this is the first article of pure hoof and horn-dust made.

I make no claim to the digester, nor to the kiln, nor to the edge-mill. They are all in use, or nearly similar ones are in use, in various mechanical operations.

What I claim as my invention, and desire to secure by Letters Patent, is—

The process of making horn-dust as a fertilizer, by the combination of steaming, drying, and crushing, as a whole operation, in the manner substantially as described.

D. A. TER HOEVEN.
